UNITED STATES PATENT OFFICE.

JOHN A. NASH, OF BUTLER, PENNSYLVANIA.

SWITCH-LOCKING DEVICE.

1,106,154.

Specification of Letters Patent.

Patented Aug. 4, 1914.

Application filed February 13, 1913. Serial No. 748,116.

To all whom it may concern:

Be it known that I, JOHN A. NASH, a citizen of the United States of America, residing at Butler, in the county of Butler and State of Pennsylvania, have invented 5 certain new and useful Improvements in Switch-Locking Devices, of which the following is a specification, reference being had therein to the accompanying drawing.

10 This invention relates to a switch locking device, and my invention aims to provide a simple, durable, inexpensive and adjustable lock holder by which the handle of a single or double switch blade can be locked in an 15 open position and thereby prevent the switch blade from being accidentally closed or tampered with.

My invention further aims to accomplish the above results by a mechanical construction consisting of comparatively few parts 20 that will be hereinafter specifically described and then claimed.

Reference will now be had to the drawing, wherein:

25 Figure 1 is a plan of the switch locking device in accordance with my invention, and Fig. 2 is a side elevation of the same.

The reference numeral 1 denotes a switch board and located upon said switch board is 30 a knife switch, comprising pivoted blades 3 and a handle 4. The blades 3 are adapted to engage contact posts 5 for completing an electric circuit, and in order to hold the knife switch in an open position I resort to 35 the use of an adjustable device that can be positioned to lock knife switches of various sizes in an open position when occasion so requires.

The switch board 1 is provided with an 40 adjustable screw 6 that is held in adjusted

position by jam nuts 7 arranged upon said screw and engaging both faces of the switch board. The screw 6 is adjustable in a plane at right angles with respect to the plate of the switch board.

45 The upper end of the screw 6 is provided with a conventional form of lock 8 having a pivoted shackle 9. This shackle can be easily placed over the handle 4 and closed to prevent the handle 4 from being moved. 50 The lock 8 is of the ordinary and well known type commonly styled a pad lock and is operable by a key whereby the shackle 9 can be opened to permit of the knife switch being closed to complete an electric circuit. 55

It is apparent that a similar locking device can be used for retaining the knife switch in a closed position and in either instance the switch cannot be tampered with after it has been adjusted.

60 One embodiment of my invention has been illustrated, but it is to be understood that the structural elements are susceptible to such changes as fall within the scope of the appended claim.

65 What I claim is:—

A lock for blade switches having an adjustable screw arranged on the base thereof, a pair of jam nuts carried by said screw for maintaining the screw in the adjusted position, and a shackle carried on the upper end of said lock and adapted for engaging over the handle portion of a switch for locking the said switch in position.

70 In testimony whereof I affix my signature 75 in the presence of two witnesses.

JOHN A. NASH.
